CLAIM

I claim the ornamental design for a rechargeable pool cleaner, as shown and described.

DESCRIPTION

FIG. 1 is a front view of the rechargeable pool cleaner of the present design;

FIG. 2 is a back view of the rechargeable pool cleaner of the present design;

FIG. 3 is a left view of the rechargeable pool cleaner of the present design;

FIG. 4 is a right side view of the rechargeable pool cleaner of the present design;

FIG. 5 is a bottom view of the rechargeable pool cleaner of the present design;

FIG. 6 is a top view of the rechargeable pool cleaner of the present design;

FIG. 7 is a perspective view of the rechargeable pool cleaner of the present design; and,

FIG. 8 is another perspective view of the rechargeable pool cleaner of the present design.

The dash lines included, if any, depict the environment and are not part of the claimed design.

1 Claim, 8 Drawing Sheets
